(57) **CLAIM**

The ornamental design for a portion of a flashlight, as shown and described.

DESCRIPTION

FIG. 1 is a perspective view of a portion of a flashlight as seen from the front, top, right side;

FIG. 2 is a perspective view of a portion of a flashlight of FIG. 1 as seen from the rear, top, left side; and,

FIG. 3 is an enlarged perspective view of a portion of a flashlight of FIG. 1 showing parts of the design at a larger scale.

The broken lines which define the bounds of the claimed design form no part thereof. The broken lines showing the remainder of the flashlight are for illustrative purposes only and form no part of the claimed design.

In other embodiments, the ornamental features illustrated in the Figures extend around the entire circumference of the flashlight.

In other embodiments, the flashlight includes flared front and rear end portion shown in broken lines in the Figures, i.e., the rear end portion defining the flare optionally is shown in solid lines.
